ABSTRACT OF THE DISCLOSURE

A pack of fence post fasteners in which the fasteners are held in nested relation by two strips of pressure-sensitive tape extending across and adhering to opposite sides of the nested fasteners.

This invention relates in general to packaging means and, more particularly, to a plurality of fence post fasteners presented in an orderly pack.

Metal fence posts are used extensively for supporting various types of fencing material, and this material is held to the posts by metal fence post fasteners or clips. Normally five fasteners are used per post. It is customary among fence post manufacturers to pack five posts to a bundle and to include for or with each bundle a packing bag or box containing 25 or 50 fence post fasteners. By reason of their tortuous contour, these fasteners easily become entangled and interlocked within the package, often to the extent that they cannot be removed without destroying the package, and even then it is difficult to remove individual fasteners from the tangled mass.

Among the several objects of the present invention may be noted the provision of a pack of fasteners in which the fasteners are arranged in an orderly accessible manner; the provision of a pack of fasteners of the type stated in which the fasteners can be removed conveniently and individually; and the provision of a pack of fasteners of the type stated which is simple and rugged in construction and economical to assemble. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

FIG. 1 is a perspective view of a fastener pack constructed in accordance with and embodying the present invention;

FIG. 2 is a side elevational view of the fastener pack;

FIGS. 3 and 4 are sectional views taken along lines 3—3 and 4—4, respectively, of FIG. 1;

FIG. 5 is a plan view of a fastener forming part of the fastener pack; and

FIG. 6 is a fragmentary elevational view showing the pack attached to a workman's belt.

Corresponding reference characters indicate corresponding parts throughout the several views of the drawings.

Referring now to the drawings, 2 designates a pack of individual fence post fasteners 4 held together in an orderly and accessible manner by means of strips of pressure-sensitive tape 6, 8.

Each fastener 4 is formed from wire stock and includes a pair of legs 10, 12, which diverge from a common apex 14. At its opposite end, leg 10 is turned outwardly away from the plane defined by legs 10, 12, in the formation of an upturned end portion 16. Leg 12 is similarly turned outwardly in approximately the same direction at its opposite end and then downwardly again in the formation of a U-shaped hook portion 18, the legs of which lie

2

in a plane approximately perpendicular to the plane defined by legs 10, 12.

In pack 2 a plurality of fasteners 4 are arranged in nested relation (FIGS. 1 and 6) with legs 10, 12, hook portions 18, and upturned end portions 16 of adjoining fasteners located adjacent and substantially parallel to one another. Tape strips 6, 8, pass over and adhere to the opposite sides of nested fasteners 4, that is, they adhere to the oppositely presented somewhat undulated surfaces formed by a series of adjacent legs 10 and 12, thereby holding fasteners 4 in a flexible although orderly arrangement. Beyond endmost fastener 4 tape strips 6, 8, adhere to one another in the formation of an end tab 20 having an aperture 22.

5 A tape suitable for use as tape strips 6, 8, is formed from a natural-colored creped paper saturated with a tough rubber-based impregnant and having a pigmented rubber-resin adhesive applied thereto. The tape adheres to steel with a force of 38 oz./inch width, is 0.0070 inch thick, elongates 10% before breaking, and has a tensile strength of 20 lbs./inch width. Such a tape is marketed by the 3M Company, St. Paul, Minn., under the trademark SCOTCH and is designated by that company as its No. 234 General Purpose Paper Tape.

10 Another tape suitable for use as tape strips 6, 8, is No. 232 General Purpose Masking Tape also marketed by the 3M Company under the trademark SCOTCH. That tape is a natural-colored creped paper saturated with a tough rubber-based impregnant and having a pigmented rubber-resin adhesive applied to one surface thereof. The tape adheres to steel with a force of 40 oz./inch width, is 0.0075 inch thick, elongates 10% before breaking, and has a tensile strength of 20 lbs./inch width. Tapes 232 and 234 adhere instantly even on extreme contours such as the undulated surfaces formed by a plurality of fasteners 4 arranged in nested relation.

15 The foregoing values for tensile strength, thickness, elongation, and adhesive strength for SCOTCH No. 232 and No. 234 tape were determined by test methods under Federal Test Method Standard 147 and represent average values. Tape strips 6, 8, which are 1½ inches wide have been found suitable for use with fasteners 4 having a total width of approximately 3¼ inches and a wire diameter of approximately ¼ inch.

20 In use, pack 2 is included with a bundle of fence posts and contains a sufficient number of fasteners 4 for all the posts within the bundle. By passing a string or wire through aperture 22, pack 2 can be attached to one of the posts in the bundle, thereby preventing loss of fasteners 4 during shipment and handling. After the posts have been emplaced within the ground and the fencing material is to be attached to them, tab 20 is gripped and pulled back between upturned end portion 16 and U-shaped hook portion 18 of endmost fastener 4. In so doing tape strip 8 will tear along legs 10, 12, of that fastener, thereby freeing tape strip 6 so that it can be peeled back across legs 10, 12, of succeeding fasteners 4. The free end of tape strip 6 is then looped through the workman's belt and subsequently brought into adherence with itself, preferably beyond the last fastener 4 (FIG. 6). In this position fasteners 4 are held by tape strip 8 and are conveniently accessible at the workman's waist. When the workman needs a fastener 4 he merely reaches down toward his waist and pulls it from tape strip 8. Pack 2 can also be utilized without attaching it to a workman's belt. Individual fasteners 4 can be removed by pulling tab 20 back across either tape strip 6 or 8 and toward apex 14 of endmost fastener 4, thereby causing one of the tape strips to tear along legs 10, 12, as previously described. When the peeled strip is peeled still further across succeeding fasteners 4, they are main-

tained in nested relation by the torn tape strip; yet they can be easily removed for use.

At all times the fasteners 4 remaining in pack 2 are held adjacent one another in nested relation by tape strip 8. Accordingly, they cannot become entangled or interlocked. On the contrary, they are always presented in an orderly manner for quick and convenient removal.

The two tape strips need not extend across legs 10, 12, nor is it necessary that they be presented exactly opposite one another. For example, a pack of nested fasteners 4 may be assembled with one tape strip extending across the convexed undulated surface formed by the aligned U-shaped hook portions 18 and the other tape strip extending across the undulated beveled surface formed by the intersection of legs 10 and upturned end portions 16. In such a case the first tape strip would assume the U-shaped configuration of hook portions 18, while the second tape strip would lie generally in two different intersecting planes, the first being formed by the underside of aligned upturned end portions 16 and the second being formed by the underside of aligned legs 10, reference being made to FIG. 3. Although the tape strips would no longer be presented opposite one another, they would still extend across different undulated surfaces formed by nested fasteners 4, and these undulated surfaces would be located on opposite sides of the pack of fasteners.

In use each fastener 4 is pulled from the first and second tape strips, or one of the tape strips is pulled back upon itself and across a few of the endmost fasteners, thereby leaving those fasteners adhering only to the remaining tape strip. In the latter case the workman can remove the endmost fasteners merely by pulling them off the remaining tape strip. The tape strip which had been peeled back could, if desired, be looped over a workman's belt as previously described so that the workman would have fasteners 4 conveniently available at his waist.

Other arrangements for the tape strips are also possible.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

What is claimed is:

1. A pack comprising a plurality of fasteners having similar irregular contours which enable them to be arranged in nested relation; each of said fasteners having first and second legs; portions of said first and second legs lying in the same plane; said first leg having a shape which is different from the shape of said second leg; said first and second legs of said plurality of fasteners combining to form first and second surfaces respectively when said fasteners are in nested relation, said first and second

surfaces being shaped differently from one another; and holding means engaging each of said fasteners for holding said fasteners in nested relation.

2. A pack according to claim 1 wherein each of said first and second legs diverge from a common apex, said first and second surfaces being substantially continuous and oppositely presented; and said holding means is a strip of tape extending across and adhering to said first surface.

3. A pack according to claim 1 wherein said holding means are strips of tape extending across and adhering to said plurality of nested fasteners.

4. A pack according to claim 3 wherein the strips of tape are formed from creped paper saturated with a rubber-based impregnant and have a tensile strength of at least approximately 20 lbs. per inch width.

5. A pack according to claim 4 wherein the tape further comprises a rubber-resin adhesive carried by the creped paper; and the tape possesses an adhesive strength on steel of at least approximately 38 oz. per inch width.

6. A pack according to claim 2 wherein another strip of tape extends across and adheres to the surface formed by said second legs.

7. A pack according to claim 6 wherein the first leg of each fastener turns outwardly at its end in the formation of an upturned end portion; and the second leg of each fastener turns outwardly at its end in the formation of a hook portion.

8. A pack according to claim 6 wherein the strips of tape adhere to each other between the first and second legs of the endmost fastener and therebeyond in the formation of a tab, whereby when the tab is pulled toward the apex one of the strips of tape will tear along the diverging legs, thereby freeing the other strip so that it can be peeled free of the fasteners.

9. A pack comprising a plurality of fasteners having similar irregular contours which enable them to be arranged in nested relation; each of said fasteners having a center portion lying in a first plane, a first end portion lying substantially in a second plane different from said first plane, and a second end portion defining substantially a third plane different from said first and second planes; said center portions and end portions combining to form at least two different surfaces when said fasteners are in nested relation; and holding means engaging each fastener for holding said fasteners in nested relation.
